(57) **CLAIM**

The ornamental design for a foldable infant changing pad, as shown and described.

DESCRIPTION

FIG. 1 is a top plan view of a foldable infant changing pad embodying my design.

FIG. 2 is a bottom plan view thereof.

FIG. 3 is a front elevational view of thereof.

FIG. 4 is a rear elevational view thereof.

FIG. 5 is a right side elevational view thereof.

FIG. 6 is a left side elevational view thereof; and,

FIG. 7 is a front perspective view thereof, showing the infant changing pad folded to form a clutch.

The detail shown in broken lines forms no part of the claimed design.
